Richard J. Cook

ATTORNEY

UNITED STATES PATENT OFFICE.

JESSE W. SILVER, OF TACOMA, WASHINGTON.

INFORMATION DIRECTORY.

Application filed March 21, 1923. Serial No. 626,523.

To all whom it may concern:

Be it known that I, JESSE W. SILVER, a citizen of the United States, and a resident of the city of Tacoma, county of Pierce, State 5 of Washington, have invented certain new and useful Improvements in Information Directories, of which the following is a specification.

This invention relates to "Information 10 directories," and more particularly to devices of that character that are especially adapted for use on street lamp posts, or the like, for the convenience of strangers, visitors or for anyone else seeking information 15 pertaining to a city.

It is the principal object of the invention to provide a device of the above character embodying an attractive and durable housing wherein a plurality of information bearing leaves are contained, and to which access 20 may be readily had upon opening the housing.

Another object of the invention resides in the provision of means whereby the information bearing leaves and the housing will be 25 automatically closed as soon as released by a user so that the directory cannot remain in open position when it is not being used.

A still further object resides in the details of construction of the leaf supporting 30 hinges, which makes possible the use of a large number of leaves without making it difficult to have easy access to each one individually.

Other objects reside in the various details of construction of the housing for enclosing the information leaves which permits a front wall and a side wall to be 35 opened outwardly so that easy access may be had to any of the information bearing leaves.

In accomplishing these and other objects, I have provided the improved details of construction, the preferred forms of which are 40 illustrated in the accompanying drawings, wherein—

Figure 1 is a front elevation of a directory embodying the present invention, showing it in open position.

Figure 2 is a horizontal section of the same, in open position.

Figure 3 is a side view of the device particularly showing the springs for closing the door.

Figure 4 is an enlarged horizontal section of the device when closed. 55

Figure 5 is a detail view of a part of the device, showing the assembly of the hinge plates and leaves thereon.

Figure 6 is an edge view of one of the 60 information leaves.

Referring more in detail to the drawings—

1 designates, as a whole, an information directory constructed in accordance with the present invention. The main part preferably would be constructed of cast or pressed metal plates, and comprises a back wall 2, opposite side walls 3 and 4 and a front part 5 which constitutes the door of the housing. The back wall 2 is provided with rearwardly projecting transverse portions 6 and 7, respectively, near its upper and lower ends, forming seats for fitting against a supporting post or the like, and holes are provided through the ends of the seats for receiving therethrough the ends of U-bolts 8 whereby the housing may be secured to a support. Nuts, as at 9, would be applied to the ends of the U-bolts on the inner side 70 of the housing to tighten the bolts about 75 the support. 80

In the present construction, the side wall 3 is cast integral with the back wall 2 and upper and lower end walls of the housing, but the part forming the side wall 4 is made 85 independent and is hingedly attached so that it may be swung outwardly from closed position so as to assume the position as shown in Figure 2. It is connected to the back wall by means of a hinge pin 10 that extends through registering openings in supporting ears 12 and 13 that are formed respectively at the edges of the back and side wall. 90

The front forming portion 5 of the housing is likewise hingedly attached to the forward edge of side wall 4 by means of a hinge pin 15 that extends through ears 16 and 17 formed respectively on the adjacent edges of these parts; the construction is such that 95 when the parts are in closed position, the housing will be absolutely tight and will prevent the information bearing leaves therein from being soiled by weather. 100

Formed on the inner face of the side wall 105 4, near its upper and lower edges are transverse ribs 19 and 20 and extending between these is a hinge pin 21 whereon a plurality

- of hinge plates 22 are swingingly mounted. These plates extend substantially the whole length of the housing but are relatively narrow and each, at its outer or swinging edge, 5 has a hinge pin 23 mounted therein whereon a plurality of leaves 24 are hingedly supported. In the device herein illustrated, I have shown five plates 22 mounted on the hinge pin 21 and each of these supports five 10 leaves 24 whereon information may be placed. The parts are made of such size that they may be easily swung into and from the housing and can be used without any difficulty.
- 15 An important detail in the present invention, resides in the construction of the hinge plates, the leaves and the method of assembly which permits compactness of arrangement.
- 20 In the preferred construction each of the hinge plates 22 is provided with three receiving sockets 28 for the hinge pin 21 and these are so arranged that the sockets of successive plates will be supported upon each 25 other. Likewise the leaves 24 are each provided with three sockets 29 for the hinge pin 23 and these are arranged in stepped relation and are located on the pins one above the other.
- 30 In order that the housing will not remain open when it is not in use, I have provided springs 32 and 33 which are located about the hinge pins 10 and 15, respectively. The spring 32 has opposite end portions extended to bear against a supporting ear of the side wall and against the back wall in such manner that the tension of the spring will act to yieldingly urge the wall toward closing position. Likewise the spring 33 has 35 opposite end portions hooked about a supporting ear of the side wall and bearing against the front so as to yieldingly urge the latter toward closed position. With this arrangement, after the device has been in 40 use and is released, the springs will act to fold the parts together and into closed relation as shown in Figure 3.

Ordinarily information would be printed on the leaves, or posted thereon, but if it is desired, clips 36, as shown in Figures 5 and 6 could be secured to the leaves whereby information bearing cards could be removably held.

It is readily apparent that devices of this 55 character may be made in various sizes and in different proportions than herein illustrated and could be made for outside or inside use. It is also apparent that the hous-

ings of the directories could be made very ornamental so as to enhance their appearance.

Having thus described my invention, what I claim as new therein and desire to secure by Letters Patent, is:

1. In a device of the class described, comprising a housing adapted to be secured to a supporting post, or the like, a hinge pin supported within the housing, a plurality of plates having edges hingedly mounted on said pin, leaf supporting hinge pins mounted in the swinging edges of said plates and a plurality of leaves hingedly mounted on each of the latter pins.

2. In a device of the class described, comprising a housing adapted to be secured to a supporting post, or the like, and having a hingedly mounted side wall and an outwardly swinging door, a hinge pin mounted along the inner face of said side wall, a plurality of plates hingedly mounted on said pin, leaf supporting hinge pins carried between swinging edges of each of said plates parallel with the first named hinge pin and a plurality of leaves hingedly mounted on each of the said leaf supporting hinge pins.

3. A device of the class described, comprising a housing, a plurality of plates hingedly mounted on a wall of the housing about the same axial line and a plurality of leaves hingedly mounted on the swinging edges of the said plates and wherein the leaves supported by each plate are adapted to lie flatly together and the several sets of leaves are adapted to lie flatly together within the housing.

4. A directory of the character described comprising an enclosing housing having a side wall thereof swingingly supported, by a hinge pin connection, from the back wall, and having a front wall swingingly supported by a hinge pin connection from the forward edge of the side wall; said side wall and front being adapted to swing outwardly to open position, springs mounted about the hinge pins for yieldingly urging the parts to closed position, a hinge pin mounted along the inner face of the said swinging side wall, a plurality of plates hingedly mounted on said pin, hinge pins supported in the swinging edges of said plates and a plurality of information bearing leaves hingedly mounted on these pins to swing into and from the housing.

Signed at Tacoma, Washington, this 14th day of March, 1923.

JESSE W. SILVER
